JAR LIFTER

Margaret T. Sturr, Haddon Heights, N. J.

Application October 23, 1944, Serial No. 559,949

4 Claims. (Cl. 294—33)

This invention has reference to devices for handling jars and the like commonly used in the canning or packing industries while it relates, more particularly, to such a device for lifting and carrying Mason-jars and similar containers commonly used by housewives and others in the preservation of fruits, vegetables and other edibles for home consumption.

The main object of my invention is to provide an improved lifter or carrier that is simple in construction, cheaply manufactured, and which can be easily and effectively operated for handling jars and similar containers preferably employed for canning and cold-packing purposes with a minimum of danger and accidental loss of such containers.

Another object is the provision of a jar-lifter and carrier having a comparatively wide range of usefulness, that is to say it can be equally well used for lifting jars of different neck diameters and sizes.

Other objects, with ancillary advantages, of this invention will become apparent from the following detailed explanation of the preferred embodiment thereof shown by the accompanying sheet of illustrative drawings, wherein like characters of reference designate corresponding parts in all the views; while the concluding claims more particularly define the features of novelty over the prior art.

In the drawing:

Fig. 1 is a view in elevation of a preferred form of the jar-lifter constructed in accordance with this invention, said view having an intermediate portion of a clamping or locking element broken out for clearer illustration of underlying structure.

Fig. 2 is a view taken at right angles to the preceding, and showing the jar-lifter in active position or as applied to a fragmentary upper portion of a conventional Mason-jar; and,

Fig. 3 is an underside plan view of the jar-lifter.

In describing the form of this invention exemplified in the drawing herewith, specific terms will be employed for the sake of clarity, but it is to be understood the scope of said invention is not thereby limited; each such term being intended to embrace all equivalents which perform the same function for an analogous purpose.

As disclosed in the drawing the improved jar-lifter therein depicted comprises a pair of legs 5, 6, each of which is fabricated from appropriate gage wire, said legs being spirally twisted

together to provide a rigid, or short, spiraled stem-portion 7. One of the legs 5, for example, is suitably bent to form an arcual section or jaw 8 with flanking rectangular-sections 9, the latter having mutually engaged continuations that jointly define a shank 10 merging into the spiraled stem 7, aforesaid.

The other jaw 6 is complementarily-fashioned to include an opposing jaw 11, rectangular-sections 12, and a shank 13, with one leg continuation 14 extended and coiled to form a lifter or carrier-loop 15; while the free end of said loop is shaped to define a guide-eye 16, the purpose whereof is later on set forth. At this juncture it is to be noted that the respective parts 8, 9, 11 and 12 are, respectively and preferably rectangularly related. In other words, the parts 8 and 11 normally function in a substantially-horizontal plane; whereas the parts 9 and 12 are approximately vertically disposed with respect to said horizontal plane; while the shanks 10, 13 are divergently flexed or biased outwards below the spiraled stem 7, as shown in Fig. 2, for a purpose later explained.

For clamping or holding the gripping jaws 5, 6 in lifting or carrying engagement with the neck 17 of a conventional Mason-jar 18, see Fig. 2, use is made of a locking-member 19. This member 19 is preferably made of wire, of the same gage as that of the parts previously described, to include a straight portion 20, slidable lengthwise through the guide-eye 16 aforesaid, and having at its lower end a loop 21 of sufficient diameter to encircle the both shanks 10, 13 at various angular degrees of relative separation. In addition the portion 20, of the locking-member 19, is provided, at the upper end, with an angularly-related manipulator section 22, conveniently formed by bending in an obvious manner. At this point it is well to note that the free end of the loop 21 by coaction with the relatively adjoining leg continuation 10, serves to ensure direct linear travel of the locking-member 19; and prevents rotary movement of said member relative to the respective shanks 10, 13, which materially aids in applying and removing the lifter, as a unit, in respect to the jar 18. It is to be further noted that the length of the straight portion 20 of the locking-member 19 is approximately the same or slightly less than the dimension intervening the guide-eye 16 and the respective rectangular sections 9, 12 of the jaws 5, 6; while the inside diameter of the loop 21 is such as to prevent complete collapse of the shanks 10, 13 into

mutual abutment, whereby the bias of said shanks remain unimpaired.

In use the locking-member 19 is first drawn out relative to the lifter as a unit, or the loop 21 is moved towards the spiralized stem 7, with resultant and automatic separation of the jaws 5, 6 under the recoil action inhering to the initial bias imposed on the respective shanks 10, 13. The separated jaws 5, 6 are next applied to the neck 17 of the jar 18 with concurrent movement inward of the member 19 by the manipulator section 22, until the loop 21 grips the shanks 10, 13, whereupon the jaws 5, 6 become firmly and opposingly clamped to said neck 17. It will be self-evident the jar 18 can now be safely lifted, or carried, with positive assurance of non-separation of the jar neck 17 from between the jaws 5, 6 until necessary or desired.

From the foregoing it will be clearly apparent that a jar-lifter or carrier constructed as herein-before described and shown will be found particularly useful in the generality of households, during the canning or cold-packing season; and while I have explained a preferred embodiment thereof, the same is not to be considered limitative, otherwise than the prior art prescribes.

Having thus described my invention, I claim:

1. A jar-lifter and carrier comprising a pair of opposingly-influenced members respectively consisting of a length of wire bent intermediate the ends to provide a shank including mutually-engaged straight leg portions, said portions being spiralized together proximate one end to form a rigid section; a gripping-jaw at the free end of each shank straight portion including opposed rectangular extensions with an intervening integral curved connection; suspension means, at the outer end of the rigid section, consisting of an

extension of one of the spiralized portions of the bent wires formed into a lifter-loop, with its free end turned into a guide-eye; an associated slideable locking-element movable through the guide-eye and embodying a loop at one end encircling the shank straight portions; and a manipulator projection at the outer end of the locking element, whereby the respective movable-members are closable inward with the gripping-jaws locked to a jar neck.

2. A jar-lifter and carrier as defined in claim 1, wherein the opposingly-influenced members are divergently biased outward from the inner end of the spiralized rigid section; and the gripping-jaw shank rectangular extension, with the integral curved connection, are respectively disposed in planes at approximately right-angles to one another.

3. A jar-lifter and carrier as defined in claim 1, wherein the slideable-element consists of a length of wire of the same gage as that forming the opposingly-influenced members; such length of wire being provided at one end with a loop, in a plane at right angles thereto, and having its free end arranged to coact with the adjoining leg portion; and a manipulator at the other end of said wire formed by retroversion of the latter into angularly-related position.

4. A jar-lifter and carrier as defined in claim 1, wherein the slideable locking-element loop is of an inside diameter to prevent complete collapsing of the gripping jaws into mutual abutment, and the length of the straight portion of said locking element does not exceed that intervening the guide means and the rectangular extensions of the opposingly-influenced members.
